UNITED STATES PATENT OFFICE.

JOHN MARION CREAMER, OF KNOXVILLE, TENNESSEE.

DESIGN FOR AN ELECTRIC SWITCHBOARD.

SPECIFICATION forming part of Design No. 33,303, dated October 2, 1900.

Application filed July 23, 1900. Serial No. 24,610. Term of patent 14 years.

To all whom it may concern:

Be it known that I, JOHN MARION CREAMER, a citizen of the United States, residing at Knoxville, in the county of Knox and State 5 of Tennessee, have invented and produced a new and original Design for Electric Switchboards; and I do hereby declare the following to be a full, clear, and exact description of the invention, such as will enable others 10 skilled in the art to which it appertains to make and use the same, reference being had to the accompanying drawing, and to letters of reference marked thereon, which forms a part of this specification.

15 The drawing is a front elevation of an electric switchboard embodying my new design.

A is the usual base.

B B is a framing surrounding the base A.

C C are the usual straps, arranged in pairs, 20 each pair having between its two members disks D, substantially equidistant from each other from center to center, and each being separated from the adjacent straps by a short space. Adjacent to each disk each 25 strap has a curved notch C', corresponding to a similar curved notch D' in the adjacent portion of the adjacent disk, the said two curves forming arcs of a circle having its cen-

ter between said strap and disk. Said disks are arranged in rows in two directions— 30 namely, parallel to said straps and at right angles to said straps.

The leading feature of my new design consists in the pairs of straps and the disks arranged in rows between said straps, said disks 35 and straps being notched, as already set forth, and said disks being arranged in rows at right angles to said straps, the disks of some of such rows at right angles to said straps being substantially circular in outline, while the 40 disks of others of such rows are of angular form, the rows of the two forms being distributed with approximate regularity.

Having described my invention, what I claim as new, and desire to secure by Letters 45 Patent, is—

The design for an electric switchboard, as herein shown and described.

In testimony whereof I affix my signature, in presence of two witnesses, this 17th day of 50 July, 1900.

JOHN MARION CREAMER.
